UNITED STATES PATENT OFFICE.

ROSS M. G. PHILLIPS, OF WEST HAVEN, CONNECTICUT.

COOKING APPARATUS.

1,161,522.

Specification of Letters Patent. Patented Nov. 23, 1915.

Application filed August 10, 1914. Serial No. 856,045.

To all whom it may concern:

Be it known that I, Ross M. G. PHILLIPS, a citizen of the United States, residing at West Haven, in the county of New Haven 5 and State of Connecticut, have invented a new and useful Improvement in Cooking Apparatus; and I do hereby declare the following, when taken in connection with the accompanying drawings and the characters of reference marked thereon, to be a full, clear, and exact description of the same, and which said drawings constitute part of this application and represent, in—

Figure 1 a view partly in right hand side 15 elevation and partly in vertical section, of a cooking apparatus constructed in accordance with my invention, the food-compartment being sealed. Fig. 2 an underside view thereof, the legs being broken away. Fig. 20 3 a broken view in vertical section of the lower end of the food compartment on the line *a*—*b* of Fig. 2 and showing the shutter of the ingress air passage in its closed position. Fig. 4 a broken detail view showing 25 the means for raising the outer end of the shutter against its seat. Fig. 5 a broken view in front elevation of the lower end of the apparatus showing the preheater in its centered position. Fig. 6 a broken detail 30 sectional view of the burner-swivel. Fig. 7 a broken detail view in vertical section showing the lower end of the timing apparatus, and showing the means employed for holding the shutter and the damper of the 35 apparatus in their open positions. Fig. 8 a view in right hand side elevation showing a cooking apparatus of the oven type with my improved means applied to it. Fig. 9 a plan view thereof. Fig. 10 a broken view 40 in vertical section on the line *c*—*d* of Fig. 7 showing the damper employed to close the air egress passage of the modified apparatus. Fig. 11 a broken detail view showing the relief-valve with which the valve 45 71 closing the egress-draft-passage is provided. Fig. 12 a corresponding view of the relief-valve with which the damper of the modified form shown in Figs. 8, 9 and 10 is provided.

50 My invention relates to an improvement in cooking apparatus of the type in which a food-compartment is provided with ingress and egress draft-passages which are automatically closed for the sealing of the 55 compartment after the same has been heated

for a predetermined time, the object being to produce a simple, convenient and economical apparatus of the character described.

With these ends in view, my invention 60 consists in a cooking apparatus having certain details of construction and combinations of parts as will be hereinafter described and pointed out in the claims.

In carrying out my invention as shown in 65 Figs. 1 to 7 inclusive, I employ a normally stationary but removable, cylindrical food-container 2 having a cooking-compartment 3, formed in its bottom with a concentric ingress draft-passage 4 and provided with 70 a double-walled insulated cover 5 having a concentric egress draft-passage 6. As shown, the food-container 2 has an inner wall or shell 7 and an outer wall or shell 8, the annular space between these walls being 75 filled with any suitable insulating material 9, such as a compound of asbestos.

The inlet draft-passage 4 is closed and sealed by means of a horizontally arranged closure or shutter 10 having oscillating and 80 vertical movement. The said shutter is furnished at its inner end with a depending hub 11 turning upon a stud 12 upon which it is held by a nut 13 applied to the threaded lower end of the said stud the upper end of 85 which is screwed into the edge of a circular plate 14 formed upon its lower face with an annular sealing-rib 15 which is set into a circular opening 16 formed in a rectangular sheet metal base 17 supported upon legs 90 18. The said plate 14 is formed in its upper face with a shallow, circular recess 19 receiving an insulating ring 20 of asbestos or other material upon which the food-container 2 is seated as clearly shown in Fig. 3. 95 The said hub 11 is encircled by a helical spring 21 arranged to exert a constant effort to swing the shutter 10 into position to close the ingress draft-passage 4, this swinging movement being arrested by a stop-lug 22 100 upon the lower face of the plate 14.

Provision is made for a slight vertical movement of the hub 11 upon the stud 12 so that the spring 21 exerts an upward pressure on the shutter for the purpose of firmly seating the upper face thereof against the sealing-rib 15. This provision for the vertical movement of the shutter also makes its oscillating movement easier, compensates for wear and inequalities of fitting. 110

To further insure the seating of the shutter 10 against the rib 15, I by preference provide the outer end of the shutter with a lifting-finger 23 which engages with a spring-finger 24 secured by screws 25 to the lower face of the plate 14, and shaped to act as a lifting-cam when the finger 23 rides up over it, whereby the outer end of the shutter is lifted just before it comes to a stop and 10 jammed against the lower face of the sealing-rib 15. For the same purpose, I employ a corresponding lifting-finger 26 fastened by screws 27 to the base 17 and arranged in position to lift the inner end of the shutter just 15 before the same comes to a stop. The screws 25 and 27 pass upward through the base 17 into the plate 14, but this detail is immaterial.

For oscillating the shutter, I employ, as 20 shown, a link 28 pivoted to it near its hub 11 and connected with the arm 29 of a bell-crank lever fastened to the lower end of a rock-shaft 30 the upper end of which is provided with a lever 31 connected with the rear 25 end of a horizontal link 32 the forward end of which is pivoted to the inner end of an operating-rod or manual 33 passing through the lower end of the casing 34 of a timing mechanism and furnished at its projecting 30 forward end with an operating-handle 35. To provide for automatically shutting off the gas simultaneously with the closing of the draft-passages 4 and 6, the said link 32 is formed with a slot 36 receiving a coupling- 35 stud 37 carried by an arm 38 connected with the valve-plug 39 of a gas-cock 40 entered at one end by a gas-supply pipe 41 and having its opposite end connected by an elbow 42 with a short nipple 43 entering a chambered 40 bracket 44 depending from the base 17 to which it is fastened. The said bracket 44 is formed with a depending tapering trunnion 45 upon which a yoke-like burner-carrier 46 turns as a swivel, the said burner-carrier having a tapered opening to receive 45 the trunnion 45, and being held thereupon by a screw 47. A short nipple 48 mounted in the burner-carrier 46 enters a mixing-chamber 49 located at the outer end of an 50 arm 50 of the preheater or burner 51 which is additionally supported by means of a heavy wire frame 52 held in place by lugs 53 upon the bottom of the burner, and having their outer ends fastened in the respective arms of the burner-carrier 46, one end of the wire being furnished with a handle 54 by means of which the burner is manually swung into its heating and lighting positions, it being necessary, or at least highly 55 desirable, to adapt the burner to be swung to one side away from the food-container into the open air at the time of lighting it to avoid danger of explosion due to a possible accumulation of air and gas in the food-container. The said bracket 44 is formed, as

shown, with a vertical passage 55 extending downward into the trunnion 45 and intersecting a circumferential passage 56 formed therein and opening into the short nipple 48 leading into the mixing-chamber 49. As the 70 movement required to open the shutter or closure 10, is greater than the movement required to operate the gas-cock 40, the slot 36 is provided to offset this excess of movement.

To provide for closing the egress air-passage 6, in the cover 5, simultaneously, or substantially simultaneously with the closing of the ingress draft-passage 4, the short arm 57 of the bell-crank lever aforesaid is connected with a rearwardly extending link 58 attached to the crank-arm 59 of a rock-shaft 60 journaled in brackets 61, 62, upon the under face of the base 17. At its inner end, the said rock shaft 60 is provided with a lifting-arm 63 engaging with the lower end of a vertically arranged lifting-rod 64 inclosed in a vertical tube 65 resting at its lower end upon the base 17. The projecting upper end of the rod 64 carries a yoke 66 receiving between its arms the outer end of a rocking-lever 67 hung on a stud 68 in a bracket 69 fastened to the top of the cover 5. The inner end of the lever 67 has mounted in it, the stem 70 of a suitable valve 71 closing the egress draft-passage 6 in the cover 5. As 95 shown, the stem 70 is provided with a knob 72. The said cover 5 is held in place upon the food-container 2 by pivotal clips 73 of any approved construction.

Instead of fastening the lifting-arm 63 directly to the rock-shaft 60, it is mounted loosely thereupon, and furnished with a stop-finger 63^a co-acting with a corresponding stop-finger 63^b formed upon a collar 63^c fastened upon the shaft 60, the said fingers 63^a and 63^b being normally held in contact by a helical spring 63^d encircling the shaft 60 and engaged at one end with the under face of the arm 63, and at the other end fastened to the shaft. The train of parts 100 employed to close the valve 71 have a movement in excess of the movement required to merely seat it, this excess of movement being compensated for by the spring 63^d which, as the movement of the parts passes the 105 amount required to seat the valve, results in the separation of the stop-fingers 63^a and 63^b, leaving the valve 71 seated under the tension of the spring 63^d.

To provide for automatically closing the 110 ingress and egress draft-passages 4 and 6 and for shutting off the fuel-supply at a predetermined time, I employ as herein shown, a timing apparatus which may, however, be replaced by any automatic means, such, for instance, as a thermostat. The timing-apparatus herein shown is constructed on the principle of the timing apparatus fully shown and described in my pending application filed August 1st, 1913, Serial No. 115 125 130

782,245, and therefore need not be detailed herein. The said timing apparatus so far as herein shown, is inclosed in a casing 34 mounted upon the right hand corner of the front of the base 17. It is provided with a graduated timing-dial 74 (Fig. 5) swept by a pointer 75 at the upper end of a setting-lever 76 hung upon the projecting outer end of a center-arbor 77 and provided at its lower end with a handle 78. The said arbor 77 carries a timing-disk 80 having a radial timing-slot 81 receiving a timing-pin 82 mounted in a timing-lever 83 hung upon a stud 84 and furnished at its opposite end with a handle 85 projecting through a segmental slot 86 in the casing 34. The said timing-lever 83 is connected by a link 87 with a releasing-lever or trigger 88 hung upon a pivot 89, provided with a forestalling handle 90 projecting through the casing 34, and formed with a notch 91 which, as it were, shuts down into a trigger-notch 92 in the operating rod 33, as shown in Fig. 7, so that the shoulder 93 of the notch 92 may be brought to a bearing upon the adjacent face of the lever 88 which acts as a latch for holding the shutter 10 in its open position with respect to the ingress draft-passage 4, and the valve 71 in its open position with respect to the egress draft-passage 6, and also acts to maintain the gas-cock 40 in its open position. At the expiration of the time to which the timing apparatus has been set by means of the setting lever 76, a spring 94 lifts the timing-lever 83 through a distance represented by the length of the slot 81, whereby the link 87 abruptly lifts the lever 88 out of engagement with the shoulder 93 of the rod 33 which is now retracted by a helical spring 95, the outer end of the rod 33 at this time moving through a bore 96 in the base 97 of the casing 34 as shown in Fig. 7.

As herein shown, the cylindrical food-container 2, though normally locked upon the base 17, is adapted to be removed therefrom by its provision at its lower end with locking-pins 98 which are entered into inclined channels in the upper ends of retaining-arms 99 cast integral with the plate 14.

Preferably I employ a thermostone 100 supported above the bottom of the food-compartment 3 upon steps 101 by means of which it is raised sufficiently not to interfere with the ingress draft. As shown, the thermostone 100 provides a mounting for a food-rack 102 provided at its upper end with a thermostone 103. Either or both of the thermostones may be employed as desired, or both may be dispensed with. The food-rack 102 as shown, has handles 104.

In the modified construction shown by Figs. 8 to 10 inclusive, my invention is shown as applied to a cooking apparatus of the stationary oven type. As shown, a rec-

tangular double-walled insulated oven 105 on legs 106 is formed in its bottom with an ingress draft-passage 107, and in the middle of its upper rear edge with an egress draft-passage 108. The said passage 107 is closed 70 and sealed by an oscillating and lifting shutter 109, while the passage 108 is closed and sealed by a closure in the form of a damper 110.

For the operation of the shutter 109, I employ a link 111 pivoted to it and at its opposite end to an arm 112 on the lower end of a vertical rock-shaft 113 provided at its upper end with an arm 114 connected by a link 115 with the reduced latch portion 116 of an operating-rod 117 entering the casing 118 of a timing mechanism of any approved construction, the said latch portion 117 of the rod being provided with a setting-handle 119. The rock-shaft 113 is 80 also provided with an arm 120 connected by a link 121 to a crank-arm 122 at the upper end of the valve-plug 123 of a gas-cock 124 entered by a gas-pipe 125 connected by an elbow 126 and a T-connection 127 with a gas-supply pipe 128. At its opposite end, the gas-cock 124 is attached to an elbow 129 connected by a nipple 130 with a fitting 131 formed with a tapering-trunnion 132 on which the burner-carrier 133 is swiveled, 90 the details of the gas-passages in the trunnion and carrier being the same as already described. The said burner-carrier 133 carries a short nipple 134 entering a mixing-chamber 135 at the outer end of a burner-arm 136 the inner end of which terminates in the burner or preheater 137 which is in part supported by a heavy wire frame 138 the inner ends of which pass through the arms of the said burner-carrier, one end of 100 the wire being extended to form the handle 129. The shutter 109 is provided with a helical spring 140 by means of which it is 105 swung into its closed position. The same means may be employed for lifting the shutter 109 as already shown and described. For the closure of the egress draft-passage 108, the link 115 is furnished with a swiveled head 141 connected by a long rod 142 with an arm 143 upon a rock-shaft 144 110 adapted to raise the damper or closure 110.

Without going further into details, it will be understood that in the modified or oven form of my apparatus, the ingress and egress draft-passages and the gas-cock are 120 simultaneously operated at the expiration of a predetermined time for the sealing of the oven, the ingress draft-passage being sealed by means of a shutter interposed between the said passage and a preheater located on 125 the outside of the oven.

The two forms of apparatus are, however, substantially the same and operate on the same principle. The details of this construction may, of course, be widely varied 130

without departing from my invention. The modified form of my improved apparatus as shown in Figs. 8 to 10 inclusive is not shown as furnished with thermostones, but it may be furnished with either, the upper or the lower, or both upper and lower thermostones as shown for the apparatus of the preceding figures.

By preference, though not necessarily, the 10 valve 71 employed for the closure of the egress draft-passage 6 (Fig. 1) is provided with a relief-valve to permit the escape of steam rising from the food. As shown in Fig. 11 this relief-valve comprises a ball- 15 valve 145 held in place by a plate 146 having a seat 147 and a vent 148. The ball 145 is located in a valve-chamber 149 opening into a vent passage 150 in the valve-stem 70. The relief-valve shown in Figs. 10 20 and 12 consists of a threaded nipple 151 mounted in the damper 110 and having a relief-passage 152 opening into a valve-chamber 153 containing a ball-valve 154 supported by a cup 155 screwed upon the 25 projecting lower end of the nipple and having a vent-passage 156. The two relief- valves shown by Figs. 11 and 12 may, of course, be replaced by relief-valves of different character and construction, and may be 30 omitted altogether if desired.

I claim:

1. In a cooking apparatus, the combination with a food-compartment having an ingress draft-passage, of a heater, a closure 35 interposed between the said passage and heater and having movement in one direction for closing the said passage, and movement in another direction for sealing the same, cocking means for maintaining the closure in its open position, means for automatically releasing the said cocking means to permit the closure to close, and means for manually opening the said closure and setting the cocking means subject to the action 40 of the said releasing means.

2. In a cooking apparatus, the combination with a food-compartment having an ingress draft-passage, of a heater, a closure 45 interposed between the said passage and heater and movable in one plane for closing the said passage and in a plane at a right angle to its closing movement for sealing the said passage, cocking means for maintaining the closure in its open position, means for automatically releasing the cocking 50 means to permit the closure to close, means for moving the closure into its closed and sealing position, and means for manually opening the said closure and for setting the said cocking means subject to the action 55 of the said releasing means.

3. In a cooking apparatus, the combination with a food-compartment having a heat-ingress passage, of a heater movable 60 into heating and lighting positions with

respect to the said passage, a closure interposed between the heater and passage for closing the latter, means for automatically controlling the closing movement of the said closure, and means for manually opening the 70 said closure to permit the use of the heater in heating the compartment.

4. In a cooking apparatus, the combination with a food compartment having an ingress draft-passage, of a heater, a closure 75 interposed between the said passage and heater and having swinging and right line movement, cocking means for maintaining the closure in its open position, means for automatically releasing the said cocking 80 means to permit it to swing into its closed position, and means for manually opening the said closure and setting the said cocking means subject to the releasing action of the said automatic releasing means. 85

5. In a cooking apparatus, the combination with a food compartment having an ingress draft-passage, of a heater, a closure interposed between the said passage and heater and having closing movement in one 90 plane and sealing movement in another plane, cocking means for maintaining the said closure in its open position, means for automatically releasing the cocking means to permit the closing of the closure, means 95 for manually opening the said closure and setting the said cocking means subject to the action of the said automatic releasing means, and a fuel-valve for the heater adapted to be manually opened, and to be automatically controlled in being closed to accord with the closing of the said closure. 100

6. In a cooking apparatus, the combination with a food compartment having an ingress draft-passage and an egress draft-passage, of a heater, a closure interposed between the said ingress draft-passage and the heater, and having closing movement in one direction and sealing movement in another direction, cocking means for maintaining the closure in its open position, means for automatically releasing the said cocking means to permit the closure to close, and means for manually opening the said closure and setting the cocking means subject to the releasing action of the said automatic releasing means. 110

7. In a cooking apparatus, the combination with a food compartment having an ingress draft-passage, of a heater, a closure 120 interposed between the said passage and heater and having swinging movement in the plane of the passage for closing the same, and right line movement to the plane of the passage for sealing the same, cocking means for maintaining the closure in its open position, means for automatically releasing the said cocking means to permit the closing and sealing movements of the closure, and means for manually opening 125 130

the said closure and setting the said cocking means subject to the releasing action of the said automatic sealing means.

8. In a cooking apparatus, the combination with a food-compartment having a heat-ingress passage, of a heater, a closure interposed between the said passage and heater, cam mechanism for moving the closure against the said passage at the end of its closing movement, means for automatically controlling the closing movement of the said closure, and means for manually opening the closure to permit the use of the heater for heating the food-compartment.
- 10 9. In a cooking apparatus, the combination with a food compartment having an ingress draft-passage and an egress draft-passage, of a heater, a closure interposed between the said heater and ingress draft-passage and having movement in one direction for closing the said passage and movement in another direction for sealing the same, a closure for the egress draft-passage, cocking means for maintaining the said closures in their open positions, means for automatically releasing the cocking means to permit the closing of the said closures, means for manually opening the said closures and setting the said cocking means subject to the action of the automatic releasing means,
- 15 20 25 30

and a gas-valve automatically controlled in closing by the said releasing means and adapted to be manually opened.

10. In a cooking apparatus, the combination with a food compartment having an ingress draft-passage, of a heater, a closure interposed between the said passage and heater and having movement in one direction for closing the said passage and movement in another direction for sealing the same, cocking means for maintaining the closure in its open position, means for automatically releasing the said cocking means to permit the closure to close, means for manually opening the said closure and setting the cocking means subject to the action of the said releasing means, and a fuel-valve automatically controlled in being closed to accord with the closing of the said closure and adapted to be manually opened after the setting of the said cocking means.

In testimony whereof, I have signed this specification in the presence of two subscribing witnesses.

ROSS M. G. PHILLIPS.
